LIFT POST ESPECIALLY FOR LIFT TRUCKS

Hans A. Kegel, Bergisch Gladbach, Germany, assignor to Vereinigte Westdeutsche Waggonfabriken Aktiengesellschaft, Köln-Deutz, Germany

Application March 21, 1957, Serial No. 647,513

Claims priority, application Germany March 28, 1956

11 Claims. (Cl. 187—9)

The present invention relates to a hydraulically actuated lift post for transporting and loading devices, especially lift trucks. In most instances, such lift posts consist of a stationary and a movable post member which latter has guided thereon a slide for receiving and supporting the load. With lift trucks, the lift post is arranged at the front side of the vehicle, while the slide with the supporting fork for the load is arranged on the front side of the post. The stationary and the movable lift post portions are subjected to bending by the load, whereas the lifting cylinder carries the load only.

It is, therefore, an object of the present invention to provide an arrangement which will overcome the above mentioned drawbacks.

It is a further object of this invention to combine the lifting cylinder with the lifting post in such a manner that the total number of structural elements will be reduced thereby making it possible to reduce the total weight and also the dimensions of the lift post, particularly in lateral direction.

It is a further object of this invention to provide a lift post according to the preceding paragraphs which will make it possible with fork-equipped lift trucks to offset the post from the longitudinal central plane of the vehicle toward one or the other side, i.e. toward the right if the driver's seat is on the left side or vice versa so that the driver's view from the driver's seat will be considerably improved.

These and other objects and advantages of the invention will appear more clearly from the following specification in connection with the accompanying drawings, in which:

Fig. 1 represents a view of a lift truck equipped with a lift post according to the invention, the latter being shown in longitudinal central section.

Fig. 2 is a horizontal section through the lift post taken along the line II—II of Fig. 1.

Fig. 3 shows in perspective the upper connection of a piston rod with the movable post member for actuating the same.

Fig. 4 diagrammatically illustrates the possibility of braking the working piston at the end of the downward stroke.

Figs. 5, 6 and 7 show the connection of the load chain with the stationary post member.

Figs. 8 and 8a diagrammatically illustrate the conditions of the free lift for a lift truck equipped with a lift post according to the invention.

Fig. 9 shows a resilient upper cover plate.

Fig. 10 illustrates a lift truck as seen from above with the lift post offset laterally with regard to the longitudinal vertical plane of the lift truck.

General arrangement

The arrangement according to the present invention is characterized primarily in that the lifting cylinder is so designed as simultaneously to serve as lift post. The combination of the lift cylinder with the lift post or the

2

construction of the cylinder itself as bend-resistant beam or post considerably reduces the number of structural elements, the weight of the post, the dimensions of the post and the view of the driver of the vehicle.

5 The design of the lifting cylinder as lift post will, of course, make it necessary that the outside of the cylinder will have a profile which will make it possible to take up the occurring torsion forces. According to a most simple construction, the outside of the lifting cylinder is so 10 designed that its cross section will be rectangular or square.

In conformity with a further development of the invention, the movable post member surrounds the profiled cylinder preferably on all sides. A closed hollow cross 15 section has the advantage, as is well known, of a maximum resistance against torsion.

For a particularly satisfactory guidance of the slide it is advantageous to provide the outer post member with recesses extending on both sides of the slide and on the 20 outside thereof along the same. Preferably these recesses are arranged at a rectangle with regard to the longitudinal direction of the vehicle. The free flanges which convey the guiding forces simultaneously act as reinforcing marginal portions of the beam or post. This 25 has a favorable effect as to the saving of weight.

The longitudinal recesses of the movable post member are engaged by rollers with pivots facing each other, said rollers preferably being journaled in said slide. These 30 rollers may also be provided with conical surfaces and accordingly may be guided by inclined counter surfaces of the recesses of the post so that the same rollers will simultaneously convey forces directed in the direction of their axes.

Structural arrangement

35 Referring now to the drawing in detail, the lift post shown therein consists primarily of the stationary post member 1 and the movable post member 2. Slidably guided on the movable post member 2 is a slide 3 carrying a supporting fork 4. The stationary post member 1 is in conformity with the present invention designed as working cylinder and has reciprocably mounted therein a piston 5. On the upper end of the piston rod 6 is journaled a sprocket 7 over which passes a chain 8. This chain is preferably but not necessarily a so-called 40 flyer chain having one end thereof connected to the upper end of the stationary or fixed post member 1 while its other end is connected to the slide 3. The piston rod 6 is fixedly connected to the upper end of the movable post member 2. It will thus be evident that the slide 3 carries out a stroke which is twice as long as that of the piston and of the movable post member.

45 The fixed post member 1 serving simultaneously as working cylinder has its outside shaped so that the outer cross sectional contour of the fixed member 1 is square shaped. The fixed post member 1 is preferably produced by welding together or hard soldering of two drawn profiles along gaps 10 which for instance may be located in the plane of the neutral zone at which the bending stresses will primarily occur. It will also be 50 obvious that the square or rectangular outer contour in connection with the cylindrical bore will yield favorable resistant moments for the bending moments to be absorbed. The outer surfaces preferably form the guiding surfaces for the movable post member 2 which telescopically engages the outer surfaces of the stationary post member. In order to improve the sliding conditions, metal plates or bearing members 11 are arranged between the two post members. For manufacturing purposes, these metal plates or layers 11 are preferably 55 arranged on the outer surface of the stationary post member 1. These metal plates or layers may in view of

the elastic flexure of the post be unevenly thick so that the axial forces which subject the piston rod to buckling stresses will not move out too far from the theoretical axis. It is, of course, understood that the lifting cylinder may be designed simultaneously as post also in various other manners. Thus, for instance, a tubular cylinder could be used and could have its outside reinforced so as simultaneously to form guiding surfaces for the movable post member.

The lower end of the stationary or fixed post member 1 is by means of screws 37 connected to the transmission casing 9 which latter forms a part of the vehicle body 33. The bottom portion of the cylinder 1 is closed by a detachable lid 12 so that the piston 5 will be accessible from below whenever necessary and can be assembled from below.

The movable post member 2 forms over the major portion of its length a body which is closed on all sides. The movable post member 2 may be produced from two rolled and drawn profiles or structural members of about double-T shaped cross section, the neutral zones substantially coinciding with the vertical transverse plane A—B (Fig. 2). The two profiles or structural members may be connected directly to each other. However, according to the particular construction shown in the drawing two intermediate members 12, 13 of less cross section are respectively arranged at the rear and at the front of the post so that the chain 8 will be arranged at the rear within and at the front outside the movable post member. The intermediate members 12, 13 are primarily due to considerations in connection with the production of the double-T structural members designed as rolled steel members. The lateral protruding portions 15 of the movable post member 2 form the inner contacting surface 16 for the guiding rollers 17 of the slide 3. Inclined surfaces 18 are furthermore provided for absorbing the axial forces of the rollers 17. The double-T profiles or structural members combine the properties of an inner and outer guide with highly resistant torques against bending and with polar inertia moment against torsion.

As has been clearly indicated in Fig. 1, the movable post member 2 has its back side slit over a certain distance so that the lower end of the post member 2 can move above that range of the fixed post member 1 over which the latter is connected to the casing 9. The fixed or stationary post member 1 has its upper end provided with a slit 38 (see Fig. 5) which makes it possible that the movable post member 2 can be moved downwardly completely over the stationary part 1 in which instance the protruding portions of the head of the piston rod 6 will enter the slit 38.

The cross section through the post as shown in Fig. 2 clearly shows the eccentric journalling of the sprocket 7 on the pivot 20. The eccentricity of the axis of said sprocket corresponds to the guiding of the front portion of the chain outside the movable post 2 and also corresponds to the guiding of the rear portion of the chain inside the movable post member 2.

As will be evident from Fig. 3, the uppermost outer end of the forked portion of the piston rod 6 for the journalling of the sprocket 7 has arranged therein a transverse web 21. The front and rear ends of the web 21 engage a corresponding recess of the movable post 2. The web 21 is connected to the piston rod 6 as well as to the movable post 2 for instance by welding. The chain sprocket 7 sharply protrudes through the downwardly extending slit of the post 2 so that the chain moves in a groove outside the post as is clearly evident from Fig. 2.

With regard to Fig. 3, it may be added that this figure shows corner pieces 59 welded to two upper corners of the movable post 2. The purpose of these corner members 59 consists in reinforcing the upper free ends of the guiding path for the rollers 17. The front ledges 15 against which the rollers 17 press as shown in Fig. 2 are at the

intermediate portion of their lengths subjected to considerably less stress than their upper free ends. Therefore, the said upper free ends of the front ledges 15 have been reinforced by the corner pieces 59. Of course, if the ledges 15 are correspondingly stronger dimensioned, a reinforcement by corner pieces such as the corner pieces 59 will not be necessary.

Fig. 4 diagrammatically illustrates the piston 5 in the lower portion of the stationary post 1. As will be seen from Fig. 4 in particular, the lower end of the piston has a unilaterally inclined surface 22 which during the last portion of the downward stroke of the piston gradually closes off the passage 23 for the admission and discharge of oil under pressure. If a sudden relief of the oil pressure conduit occurs, the last portion of the piston stroke and of the movable post is braked over a certain distance so that shocks and overloads will be avoided.

Fig. 5 illustrates the connection of the chain 8 with the stationary post 1 through the intervention of a chain closure member 24 connected to post 1 by means of screws 35. The chain closure member which is shown on an enlarged scale in Figs. 6 and 7 has a transverse bore 25 and a longitudinal bore 26 for discharging leakage oil from the working cylinder which may escape along the piston seal 36 (Fig. 4). By combining the leakage discharge with the chain closure member, the corresponding structural elements can be designed shorter.

Figs. 8 and 8a diagrammatically illustrate the longitudinal dimensions or ratios for the above mentioned structure of a fixed connection between the piston rod and the movable post. The term "free stroke" as it will presently be used designates the stroke "s" from the entirely downwardly moved condition of the forks 4 up to the level to which they move until the movable post does not yet protrude above the fixed post. In other words "free stroke" designates twice the stroke from the entirely downwardly moved position of the movable post up to that level thereof at which the upper end of the fixed post is located at the level of the upper end of the movable post. In its entirely downwardly moved position, the movable post protrudes somewhat downwardly under the lower end of the movable post. At the end of the free stroke, the upper ends of both posts are at the same level. If the movable post is lifted further, a portion of the movable post and of the piston rod protrude above the head of the lifting cylinder. If, when driving through low underpasses, the post is slightly too high only the less sensitive movable post receives a shock whereas the piston rod is protected.

Due to the fact that the piston rod never protrudes above the movable post it is made possible advantageously to cover up the interior of the movable post by a plate 30 shown in Fig. 9 thereby preventing dirt and other foreign particles from entering into the interior of the movable post. The plate 30 is resiliently supported so as to be yieldable by a stroke equaling half the free stroke, so that the movement of the movable post will not be impeded when the slide 3 is in its lowermost position. Due to the small width of the post according to the present invention, the driver of the vehicle has a particularly good view. Since the post due to its rugged construction is adapted to absorb great bending forces in all directions, it is possible as will be evident from Fig. 10, to arrange the post 1, 2 at a position laterally offset with regard to the vertical longitudinal central plane of the vehicle. If the driver's seat 34 is laterally offset toward the side and is mounted on the vehicle body 33, the conditions of view for the operator are even further improved.

An internal combustion engine 39 may be employed as power source for the lift truck according to the invention. The motor 39 is arranged to drive an oil pressure pump 40 for the drive of the vehicle and is furthermore adapted to drive an additional oil pressure pump 41 for the tilting and lifting movement of the fork 4.

The oil pressure pump 40 through conduits 42 and 43 feeds two hydrostatic driving motors 44 for the two front wheels 45. The rear wheels 46 are not positively driven but are merely steered in a manner not shown in the drawing inasmuch as this steering mechanism does not form a part of the present invention. Through the intervention of a valve 48 adapted to be actuated by a lever 47, the oil pressure pump 41 feeds oil into the lift cylinder for the fork 4. This is effected through a conduit 49, and a passage 23 in the stationary post 1. Due to the direct connection of the post 1 with the transmission casing 9 and due to the direct passage of the pressure oil from the transmission casing 9 into the post 1, a high pressure conduit is avoided which would have to be arranged on the outside of the vehicle body and would be subject to damage. All pressure oil conduits for the driving lifting and tilting operation are located within the transmission casing 9 and are thus protected against damaging influences from the outside.

Leakage oil which escapes due to certain leakages of the various conduits, is collected in the transmission casing 9. Inasmuch as the transmission casing 9 simultaneously may be used as oil sump for the pump 41, and if desired also for the pump 40, any loss of oil will be avoided. The axle 50 of the rear wheels 46 is tiltable about a pivot axle 52 by means of tiltable levers 51 extending in longitudinal direction of the vehicle body 33. The rear ends of the two levers 51 are provided with a counterweight 53. When introducing pressure oil from the pressure pump 41 into the tilting cylinder 55 through the control valve 48 and the conduit 54, the entire vehicle body 33 and thus the posts 1, 2 together with the fork 4 is tilted about the axle 56 of the front wheels 45. During such a tilting movement, the inclination of the fork 4 changes as is necessary for loading and unloading the fork. The discharge of leakage oil which may pass by the piston 5 in the upper portion of the post 1 flows back into the transmission casing 9 through the chain closure member 24 connected to post 1 and through the intervention of a conduit 57.

It is, of course, to be understood that the present invention is, by no means, limited to the particular construction shown in the drawings but also comprises any modifications within the scope of the appended claims.

What I claim is:

1. A hydraulically operable lift post system for transport and loading devices, especially lift trucks, which includes: a stationary post member, a movable post member telescopically engaging the outside of said stationary post member, said stationary post member forming a cylinder provided with passage means for receiving actuating fluid and discharging the same, said movable post member having two sides thereof provided with tracks having plane main guiding surfaces substantially parallel to the longitudinal axis of said post and having auxiliary surfaces also extending substantially parallel to the longitudinal axis of said post but respectively forming an obtuse angle with the adjacent main guiding surface pertaining to the same track, a slide, roller means respectively supporting said slide and provided with cylindrical peripheral surfaces and with conical end faces for engaging said tracks along said main and said auxiliary guiding surfaces respectively whereby said roller means will absorb radial as well as axial forces, said slide being arranged for supporting a load-receiving and supporting means, and piston means reciprocably mounted in said cylinder and connected to said movable post member for actuating the same.

2. A hydraulically operable lift post for transport and loading devices, especially lift trucks, which includes: a movable post member and a stationary post member telescopically arranged with regard to each other, said movable post member being composed of two structural members of substantially I-beam cross section arranged in spaced relationship to each other, a first connecting

member having a thickness less than the thickness of said structural members and connecting the same so as to have its outer surface set back with regard to the adjacent outer surfaces of said structural members thereby confining therewith a groove open toward the outside, a second connecting member having a thickness less than the thickness of said structural members and connecting the same so as to have its inner surface set back with regard to the adjacent inner surfaces of said structural members thereby confining therewith a groove open toward the inside, said stationary post member forming a cylinder provided with passage means for receiving actuating fluid and discharging the same, plunger means reciprocably mounted in said cylinder and connected to said movable post member for actuating the same, a sprocket wheel supported by said plunger means, and a chain passing over said sprocket wheel and having one end fixedly connected to said stationary post member and having its other end arranged for supporting a slide, one branch of said chain carrying the end for connection with a slide passing through the groove open toward the outside of said post, while the other branch of said chain passes inside of said second connecting member.

3. A hydraulically operable lift post for transport and loading devices, especially lift trucks, which includes: a movable post member and a stationary post member telescopically arranged with regard to each other, said movable post member being composed of two structural members of substantially I-beam cross section arranged in spaced relationship to each other, a first connecting member having a thickness less than the thickness of said structural members and connecting the same so as to have its outer surface set back with regard to the adjacent outer surfaces of said structural members thereby confining therewith a groove open toward the outside, a second connecting member having a thickness less than the thickness of said structural members and connecting the same so as to have its inner surface set back with regard to the adjacent inner surfaces of said structural members thereby confining therewith a groove open toward the inside, said stationary post member forming a cylinder provided with passage means for receiving actuating fluid and discharging the same, plunger means reciprocably mounted in said cylinder and connected to said movable post member for actuating the same, the upper end portion of said plunger means being provided with a cutout, a sprocket wheel rotatably supported by said plunger means and arranged in said cutout, and a chain passing over said sprocket wheel and having one end fixedly connected to said stationary post member and having its other end arranged for supporting a slide, one branch of said chain carrying the end for connection with a slide passing through the groove open toward the outside of said post, while the other branch of said chain passes inside of said second connecting member.

4. A hydraulically operable lift post for transport and loading devices, especially lift trucks, which includes: a movable post member and a stationary post member telescopically arranged with regard to each other, said movable post member being composed of two structural members of substantially I-beam cross section arranged in spaced relationship to each other, a first connecting member having a thickness less than the thickness of said structural members and connecting the same so as to have its outer surface set back with regard to the adjacent outer surfaces of said structural members thereby confining therewith a groove open toward the outside, a second connecting member having a thickness less than the thickness of said structural members and connecting the same so as to have its inner surface set back with regard to the adjacent inner surfaces of said structural members thereby confining therewith a groove open toward the inside, said stationary post member forming a cylinder provided with passage means for receiving actuating fluid and discharging the same, plunger

er means reciprocably mounted in said cylinder and connected to said movable post member for actuating the same, the upper end of said plunger means being provided with two upwardly extending prong-shaped portions leaving a recess therebetween, a sprocket wheel rotatably supported by said plunger means and arranged between said prong-shaped portions, and a chain passing over said sprocket wheel and having one end fixedly connected to said stationary post member and having its other end arranged for supporting a slide, said prong-shaped portions extending upwardly beyond said sprocket wheel to confine with the periphery of said sprocket wheel a passage for said chain, one branch of said chain carrying the end for connection with a slide passing through the groove open toward the outside of said post, while the other branch of said chain passes inside of said second connecting member.

5. A hydraulically operable lift post structure for transport and loading devices, especially lift trucks, which includes: a movable post member and a stationary post member telescopically arranged with regard to each other, said stationary post member forming a cylinder provided with passage means for receiving actuating fluid and discharging the same, plunger means reciprocably mounted in said cylinder and extending upwardly substantially to the upper end of said movable post member, the upper end portion of said plunger means being provided with two upwardly extending prongs so as to form a cutout therebetween, a transverse member extending into said cutout between said prongs and connected to said plunger means and the upper end of said movable post member, and a sprocket wheel rotatably supported by said prongs and arranged within said cutout.

6. A hydraulically operable lift post structure for transport and loading devices, especially lift trucks, which includes: a movable post member and a stationary post member telescopically arranged with regard to each other, said stationary post member forming a cylinder provided with passage means for receiving actuating fluid and discharging the same, plunger means reciprocallly mounted in said cylinder and having its upper end connected to said movable post member for actuating the same, the upper end of said plunger means being provided with a cutout, a sprocket wheel rotatably supported by said plunger means and arranged within said cutout, a slide arranged for supporting load-receiving and supporting means and guided along said movable post member, and a chain passing over said sprocket wheel and having one end thereof connected to said slide and having its other end connected to said stationary post member, the axis of rotation of said sprocket wheel being offset with regard to the central longitudinal axis of said cylinder so that the chain portion connected to said slide will always move substantially along a path parallel to the path of the other chain portion extending from said sprocket wheel to the connecting point of said chain with said stationary post member.

7. An arrangement according to claim 6, in which that end portion of the chain which is connected to the stationary post member comprises conduit means having one end connected to the interior of the upper cylinder 60

portion for receiving leakage oil and having its other end connected with a discharge for the received leakage oil.

8. A hydraulically operable lift post structure for transport and loading devices, especially lift trucks, which includes: an inner stationary hollow post member forming a cylinder with passage means for receiving actuating fluid and discharging the same, said inner post member being composed of structural members with profiled outer surfaces, an outer hollow post member telescopically slidably mounted on said inner post member, said outer post member being composed of structural members having the inside thereof profiled in conformity with the contour of said profiled outer surfaces of said inner post member so as to be guided and secured thereby against rotation, the outer surfaces of said structural members of said outer post member having a contour defining guiding track means, fluid operable piston means reciprocably mounted in said cylinder and connected to said outer post member, the upper end of said outer post member being provided with a cutout, a sprocket wheel rotatably mounted in said cutout, a load carrying slide, a chain passing over said sprocket wheel and having one end connected to said inner post member and having its other end connected to said slide, and guiding roller means mounted on said slide and engaged by said track means so as to be guided thereby.

9. A hydraulically operable lift post structure according to claim 8, in which said stationary hollow post member is composed of two profiled members connected to each other along a plane located substantially within the neutral zone of the bending stresses exerted upon said stationary post member.

10. A hydraulically operable lift post structure according to claim 8, in which said outer post member is composed of two structural members of substantially I-beam cross section connected to each other along a plane substantially perpendicular to the neutral zone of the bending stresses exerted upon said outer hollow post member.

45 11. A hydraulically operable lift post structure for use in connection with a lift truck having a chassis and a pressure fluid supply system according to claim 8, in which said inner stationary hollow post member has a lower wall portion of increased thickness for connection with the chassis of said lift truck, said wall portion being provided with a passage extending through said wall portion for connection with said pressure fluid supply system of said truck.
